UNITED STATES PATENT OFFICE.

SAMUEL T. WHITAKER, OF COLUMBUS, GEORGIA, ASSIGNOR OF ONE-THIRD TO THOMAS W. BATES AND ONE-THIRD TO EDWARD B. REED, BOTH OF COLUMBUS, GEORGIA.

TYPE-WRITER CABINET.

1,144,882.

Specification of Letters Patent. Patented June 29, 1915.

Application filed August 20, 1912. Serial No. 716,100.

To all whom it may concern:

Be it known that I, SAMUEL T. WHITAKER, a citizen of the United States, residing at Columbus, in the county of Muskogee and 5 State of Georgia, have invented certain new and useful Improvements in Type-Writer Cabinets; and I do hereby declare the following to be a full, clear, and exact description of the invention, such as will enable 10 others skilled in the art to which it appertains to make and use the same.

This invention relates to improvements in typewriter cabinets of the type provided with guideways on which a typewriting machine is designed to be run substantially horizontally into and out of an inclosure, and the object in view is the increasing of 15 the efficiency of such cabinets while largely obviating expense of production and intricacies of construction.

With this and further objects in view, as will in part be hereinafter stated and in part become apparent, the invention comprises certain novel constructions, combinations 25 and arrangements of parts, as herein disclosed and claimed.

In the accompanying drawing,—Figure 1 is a view in front elevation of a cabinet embodying the features of the present invention. Fig. 2 is a horizontal section therethrough taken on the planes indicated by line 2—2 of Fig. 1. Fig. 3 is a similar section taken at right angles to the planes of 30 Fig. 2, being taken on the plane indicated by line 3—3 of Fig. 2. Fig. 4 is an enlarged, detail, fragmentary view illustrating a section through one of the carriage rollers and adjacent parts. Figs. 5 and 6 are enlarged, detail sectional views of the latch 35 and contiguous parts.

Referring to the drawings by numerals, 1 indicates a stand or table upon whose surface, 2, is mounted a housing or casing 3, which may, for convenience, have a lateral 40 extension 3', divided into pigeon-holes or otherwise according to the preference of the user. The housing 3 has its front open forming a doorway for the full dimensions of the housing, and a door 4 is hinged as at 45 5, to the front edge of the flooring of housing 3 in position to swing from a substantially horizontal position at rest on surface 2 with its upper face flush with the upper surface of said flooring to an upright position 55 closing the doorway of housing 3. Said

doorway is preferably inclined slightly rearwardly from bottom to top, so that when door 4 is in its closed or upright position it will lie slightly on an incline rearwardly and will thus be held closed by gravity if 60 not otherwise retained. Reciprocally mounted in door 4 is a latch bolt 6 having the usual tapered end 7 adapted, when the door is closed, to be held in locking engagement with the keeper 8, by spring 9, the bolt being 65 limited against excessive outward movement by collar 10 engaging the wall of the guideway for the bolt.

Embedded in the flooring of housing 3 and in the inner or upper surface of door 4 70 is a track, consisting of spaced, parallel rails 11, 11, divided transversely, as at 12, 12, at the line of jointure between the floor and the door of the housing. Rails 11 are sufficiently embedded or countersunk in the 75 material of the floor and door to have their uppermost line flush with the surface of the floor and door and intersecting the axis of the hinges 5, so that the rails, at the line of divide 12, are not notched, but fit snugly 80 and form continuous rails, when the door is open, thereby avoiding any jar to wheels passing along the track. A carriage 13 is mounted on the track, being provided with grooved wheels 14 engaging the rails, said 85 carriage being particularly constructed to support a typewriting machine, suitable sockets being preferably formed in the carriage to receive the legs of the typewriter.

The lateral shoulder 15 is formed on bolt 90 6 in position to interlock with the part 16 on carriage 13, when the carriage is in its outermost position and thereby hold the carriage and superposed machine against vibration or tendency to move rearwardly, 95 the carriage being effectively held against outward movement by upturned ends 11', 11' of rails 11 adapted to be engaged by the front wheels 14. A ring or eye 17 is formed at the inner end of bolt 6, and the 100 material of door 4 is recessed to enable access by the fingers of the operator, whereby the locking action of the latch bolt may be released.

In operation, bolt 6 will lock door 4 whenever 105 fully closed, and if the operator carelessly or otherwise fails to press the door to a fully closed position, the incline assumed by the door will prevent it from accidentally falling open. When it is de- 110

sired to open the cabinet, the eye 17 is depressed and door 4 swung downwardly, thereby exposing the contained typewriter, which may be grasped and drawn out manually, carriage 13 moving along track 11 until stopped by the outer ends thereof, whereat the carriage will be locked by bolt 6. It is particularly noted that the movement of the carriage along the track is without jar, the same as if the track were continuous, as distinguished from proposed constructions wherein a V-shaped opening is left in the track to accommodate the swinging of the door, which opening would give the typewriter two distinct and injurious jars on being withdrawn from the housing and act similarly on the return movement. When the operator wishes to dispose of the machine, in order to use the table as a desk or otherwise, it is only necessary to release bolt 6, and press the machine rearwardly along the track until it enters housing 3, and door 4 may then be closed.

25 What I claim is:—

1. In a typewriter cabinet, the combination of a housing having a doorway through which a typewriting machine may pass to and from the housing, a door hinged to the floor of the housing in position for

swinging from a substantially vertical position to a substantially horizontal position flush with said floor, and a track for sustaining the typewriter disposed with the uppermost line of the track intersecting the line of the axis of the hinge of the door and extending across portions of the door and floor and severed transversely on a substantially vertical line at the line of jointure between the door and floor. 35

2. In a typewriter cabinet, the combination of a housing having a doorway through which a typewriting machine may pass to and from the housing, a door hinged to the floor of the housing in position for swinging from a substantially vertical position to a substantially horizontal position flush with said floor, and aligned track sections embedded in the door and floor to lie flush with the upper faces thereof when the door is horizontal, the track being adapted for sustaining the typewriter disposed with the uppermost line of the track intersecting the line of the axis of the hinge of the door. 45

In testimony whereof I affix my signature in presence of two witnesses.

SAMUEL T. WHITAKER.
